[57] CLAIM

The ornamental design for a multigrooved rotatory brush cutting tool top plate, as shown and described.

DESCRIPTION

FIG. 1 is a bottom plan view of the instant multigrooved rotatory brush cutting tool top plate;

FIG. 2 is a lateral plan view thereof;

FIG. 3 is a second lateral plan view thereof;

FIG. 4 is a top plan view thereof; and,

FIG. 5 is a third lateral plan view thereof.

The broken line showing is for illustrative purposes only and forms no part of the claimed design.
